(57) **CLAIM**

We claim the ornamental design for a kitchen hood, as shown and described.

DESCRIPTION

FIG. 1 is a perspective view of a kitchen hood showing our new design in a first position of use;
 FIG. 2 is a front elevation view thereof;
 FIG. 3 is a rear elevation view thereof;
 FIG. 4 is a left side elevation view thereof;
 FIG. 5 is a right side elevation view thereof;
 FIG. 6 is a top plan view thereof;
 FIG. 7 is a bottom plan view thereof;
 FIG. 8 is a perspective view of the kitchen hood of FIG. 1 shown in a second position of use;
 FIG. 9 is a front elevation view thereof;
 FIG. 10 is a rear elevation view thereof;
 FIG. 11 is a left side elevation view thereof;
 FIG. 12 is a right side elevation view thereof;
 FIG. 13 is a top plan view thereof; and,
 FIG. 14 is a bottom plan view thereof.

The broken lines shown in FIGS. 6 and 13 depict portions of the kitchen hood that form no part of the claimed design.
